NELS T. NELSON, OF ATTLEBORO, MASSACHUSETTS, ASSIGNOR TO J. F. STURDY'S SONS COMPANY, OF ATTLEBORO FALLS, MASSACHUSETTS, A CORPORATION OF MASSACHUSETTS

EXTENSION DEVICE

Application filed November 5, 1928. Serial No. 317,378.

This invention relates to an extension device for a wrist watch strap; and has for its object to provide means by which an increased extension may be had by a folding relation of the different sections and yet a construction which is not of excessive thickness.

A further object of the invention is to provide a means for adjustment of the working size of the strap by adjusting the point of the hinging or pivoting of one of the sections to another.

A still further object of this invention is to provide sections which unfold from each side of a section in which they are housed or secured when the device is in its contracted position.

With these and other objects in view, the invention consists of certain novel features of construction, as will be more fully described, and particularly pointed out in the appended claims.

In the accompanying drawings:

Fig. 1 is a top plan view of the extension device in contracted position.

Fig. 2 is a similar view but showing the sections in unfolded or extended position.

Fig. 3 is a sectional side view of the sections in their unfolded position.

Fig. 4 is a perspective view of the body section.

Fig. 5 is a perspective view of the cover section.

Fig. 6 is a perspective view of the plate section for hinged connecting the body and cover sections.

Fig. 7 is a perspective view of the plate section which is hinged to the body section.

Fig. 8 is a perspective view of a section hinged to the section of Fig. 7 and in turn attached to one end of the strap part.

Fig. 9 is a sectional view showing the parts in folded position.

In wrist straps particularly for wrist watches, extension devices are employed for temporarily lengthening the wrist strap to permit passing of the same over the hand of the wearer without completely detaching and separating any of its parts, and in such a construction it is found desirable to provide an enlargement which will allow the strap to be

easily passed over the hand of the wearer or lengthened sufficiently to loosely fit the largest part of the hand over which it must be passed; and in order to provide a foldable construction having these desirabilities I have provided a larger number of sections to be folded one upon another in a nesting relation than has been common in practice and have made these sections of sheet metal plates to take up the minimum amount of space and permit the same to lie closely one upon the other when in position between the body and cover sections. I have hinged these plates in such a manner that the unfolding and enlarging movement is from each side of the centrally located body so that the enlargement is in a measure equally distanced from the ends of the strap which attach to the watch. And in this construction, I have provided a means for adjusting one of the plate sections at its point of pivoting so that an adjustment of the working size of the strap may be provided which together with the strap adjustment also permits the centralizing of the device with respect to the ends of the strap; and the following is a detailed description of the present embodiment of this invention illustrating the preferred means by which these advantageous results may be accomplished.

With reference to the drawings, 10 designates one strap part and 11 the other strap part which parts are connected by a foldable extension device consisting of a body section 12 and a cover section 13, each of which is of channel shape having side walls 14 and 15. These two sections are connected by a plate section 16 hingedly attached as at 17 to the body section and provided with a loop 18 at its other end to receive a pivot pin 19 which may selectively engage any one of a pair of oppositely disposed openings 20 in the side walls 15 of the cover section for a size adjustment to fit the wrist of the wearer.

The strap part 11 is provided with a tip 21 thru which a pin 22 extends to connect it to the cover section 13. This pin 22 also may selectively engage one of the openings 20 in the side walls 15 to provide an additional means of size adjustment for the encircling length of a strap.

The other strap part 10 is also provided with a tip 23 which is connected to the body section 12 by means of a pair of plate sections 24 and 25 hinged to each other and to the body 5 and the tip 23 so that the same may be folded one upon the other as illustrated in Fig. 9, between the side walls 14 of the body section 12. The sections 24 and 25 are first folded into the body 12 and then the intermediate plate section 16 is folded over the section 24 and 25 and offset at 26 to permit this section to lie snugly against these two folded sections whereby a compact arrangement of the section is provided which may be easily and 15 quickly unfolded into the extended length when desired.

The hinge relation between the different sections may be of any suitable form, I having shown here an eye on one section to be 20 placed in line with a pair of spaced eyes on another section to receive a pintle or pivot pin to retain the sections in hinge relation.

In order that the sections may be held in their folded relation when the device is worn 25 as a wrist strap I provide any desirable means between the cover and body sections to releasably retain these sections together and for 30 illustrative purposes I have shown projections or detents 27 extending outwardly from the side walls 14 of the body sections to engage in recesses 28 in the side walls of the cover section which side walls are resilient to cause a snapping engagement between these 35 parts to retain the sections in their folded position against the accustomed strains due to the enlargement of the wrist by the muscular movements therein.

It will be apparent that the five sections provided may assume an end to end position 40 affording an extremely great enlargement in the size of the wrist strap and yet these sections upon being foldable one over the other permit a contraction to the wrist encircling size of the wearer with means for adjusting 45 this size between the different sections which are hinged together.

The foregoing description is directed solely 50 towards the construction illustrated, but I desire it to be understood that I reserve the privilege of restoring to all the mechanical changes to which the device is susceptible, the invention being defined and limited only by the terms of the appended claims.

I claim:

- 55 1. In a wrist strap having two strap parts, an extension device comprising a body section, a cover section, an intermediate plate pivotally connecting said body and cover sections and foldable therebetween and a plurality of hinged plates hinged to one of said sections to fold between said sections and connect one end of one strap part thereto and means for connecting one end of the other strap part to the other section.
- 60 2. In a wrist strap having two strap parts,

an extension device comprising a channel body section, a channel cover section, an intermediate section pivotally connecting said body and cover sections and foldable therebetween and a plurality of hinged sections hinged to one of said channel sections and foldable therein to connect one end of one strap part thereto, and means for connecting one end of the other strap part to the other channel section.

3. In a wrist strap having two strap parts, an extension device comprising a body section, a cover section, an intermediate section pivotally connecting said body and cover sections and foldable therebetween, means for changing the position of one of said pivotal connections, means for connecting one end of one strap part to the cover section, and means for connecting an end of the other strap part to the body section.

4. In a wrist strap having two strap parts, an extension device including a body section, a cover section, an intermediate section hinged at one of its ends to one of said sections, the other of said sections having side walls with a series of openings therein, and means for adjustably pivotally connecting the other end of said intermediate section to the section having side walls, comprising a pin to selectively extend into said openings to hingedly connect the other end of said intermediate section to said side walls.

5. In a wrist strap having two strap parts, an extension device comprising a body section, a cover section, an intermediate plate pivotally connecting said body and cover sections and foldable therebetween and a plurality of hinged plates hinged to one of said sections to fold between said sections and connect one end of one strap part thereto, means for connecting one end of the other strap part to the other section, and means to releasably secure said body and cover sections together to prevent unfolding of said plates therebetween.

In testimony whereof I affix my signature.

NELS T. NELSON.
